UNITED STATES PATENT OFFICE.

LAWRENCE C. NELSON, OF CHICAGO, ILLINOIS, ASSIGNOR TO STEWART MANUFACTURING CORPORATION, OF CHICAGO, ILLINOIS, A CORPORATION OF DELAWARE.

CARRIAGE-CURTAIN-WINDOW FRAME.

Application filed October 24, 1921. Serial No. 509,891.

To all whom it may concern:

Be it known that I, LAWRENCE C. NELSON, a citizen of the United States, and a resident of the city of Chicago, in the county of Cook 5 and the State of Illinois, have invented certain new and useful Improvements in Carriage-Curtain-Window Frames, of which the following is a specification, reference being had to the accompanying drawings, forming 10 a part thereof.

The purpose of this invention is to provide an improved construction of a carriage curtain window frame, particularly designed to provide for cushioning the window glass on 15 the frame at both sides, and also to render the two frame members identical in form so that they may be stamped, cast or molded in the same die or mold. It consists in the 20 elements and features of construction shown and described as indicated in the claims.

In the drawings:—

Figure 1 is an inner side plan view of one of the frame members of a carriage curtain window embodying this invention.

Figure 2 is a section at the line, 2—2, on Figure 1, cutting through the entire frame, curtain fabric and glass.

Figure 3 is a similar section at the line, 3—3, on Figure 1, showing the parts dissected and spaced from each other for more clearly distinguishing their respective features.

Figure 4 is a section at the line, 4—4, on Figure 1, similar in character to Figure 3.

Figure 5 is a view similar to Figure 2, showing a modification.

The window frame embodying this invention comprises two metal frame members, 1, which are identical in form, both in contour 40 and cross-section and in the location and distribution therein of the various features for engaging the curtain fabric and the window glass between them. Each of these frame members, 1, is rabbeted at one edge 45 as shown at 1^a, the rabbets facing each other when the two members are mounted face to face with the glass and between them, and the two rabbets together forming a recess in 50 which the margin of the glass, 3, is engaged throughout its entire periphery. In the face of the rabbet parallel to the plane of the glass, there is formed a groove extending entirely around the frame for lodgment therein of a gasket, 5, also extending entirely 55 around the inner margin of the frame, the

two gaskets, 5, 5, protruding into the rabbet space for affording seating for and gripping the glass on both sides as most clearly seen in Figure 2. Preferably the groove is right-angular in cross-section the plane which bisects the right angle being at right-angles to the face of the rabbet in which the groove is formed and, therefore substantially at right angles to the plane of the face of the glass which is engaged by the gasket. Preferably also these gaskets have their face upon which the glass seats flat and in the plane of the face of the glass and at right angles to said plane bisecting the groove. When thus constructed, the clamping of the 60 two frame members, 1, 1, together for gripping the glass causes the gasket to be compressed into the right-angle groove directly 65 in the plane bisecting the groove, with a tendency to wedge into the groove equally 70 from both sides, and thereby with the tendency of the gasket to spread equally both ways from said bisecting plane on the surface of the glass, as a result of the compression 75 by which the glass is gripped.

For gripping the curtain fabric between the two frame members at the portion of the width of said frame members outside the periphery of the glass, there are formed in the facing surfaces of said frame member, 80 co-operating male and female members which are engaged with each other when the two frame members are clamped together, engaging the fabric between them in the process, in the recess into 85 which the co-operating projection protrudes. These co-operating male and female features comprise two sorts, the first sort being dowell 90 projections, 7, and co-operating sockets, 8, said projections, 7 being preferably conical 95 and comparatively sharp pointed so that they may penetrate the fabric of the curtain in the process of clamping the two frame members together upon the same.

The other of these co-operating male and female members are respectively elongated slight upraises or flat bosses 9 and correspondingly formed and extended recesses, 10, the recesses being slightly more extended in the plane of the face of the frame 105 member than the bosses, so that the fabric of the curtain gripped between them may be pressed into the recesses in the gripping process. These bosses and recesses, 9 and 10, beside the general function of affording 110

a very secure grip of the frame members upon the curtain, may be positioned at proper points in the contour of the frame, and particularly with respect to its curves, 5 to take up any puckers or slack in the curtain fabric which results from the curves or other irregularities of contour of the frame. This feature, however, is not a part of the present invention, being the subject matter, 10 in part, of my pending application No. 471,844 filed May 23, 1921, and this function of these features is not designed to be illustrated or described in this case.

It is convenient and desirable to locate the 15 dowell pins and sockets as shown in the drawing, within the limits of the bosses and recesses, 9 and 10; and as shown, a dowell projection, 7, is located near each end of each upraise or boss, 9, and a dowell socket, 20 8, is similarly located near the end of each of the recesses, 10.

It is convenient and desirable, for giving the maximum gripping efficiency to the interlocked projections and recesses of both 25 sorts, to locate the screws which clamp and secure the two frame members together at the vicinity of these interlocking recesses and projections; and for that purpose substantially at the middle point of each of the 30 elongated bosses and recesses, 9 and 10, and preferably at the inner margin thereof, so as to be substantially at the middle of the width of the frame member there are holes 35 for clamping screws, 12. These holes in one of the frame members are tapped as indicated at 13, and in the other frame member are countersunk, as indicated at 14, for the thread and head, respectively of the clamping 40 screws.

45 15, 15, are narrow longitudinal upraises or ribs, four in all,—two upon each of the frame members near diagonally opposite corners, so that when the two frame members are applied to each other with the glass and curtain fabric between them, one of these ribs will be found near each corner, and all four in the same relation to the four corners, respectively,—that is, inward therefrom on the longer side of the frame. The 50 purpose of these ribs is to grip certain reinforcing straps, 16, which seat in recesses, 15^a, and assist in sustaining the weight of the frame in the curtain preventing it from distorting the latter. Two dowell projections, 17, 17, are preferably provided within the length of each of the ribs, 15, symmetrically situated with respect to the ends of the ribs and in the plane face of the frame member at the point adjacent to the diagonally 55 opposite corners which are without the ribs, the plane faces upon which the ribs grip,—corresponding dowell sockets, 18, are provided for engagement of the dowell projections, 17.

60 65 An important and characteristic feature

of the construction of the frame members in respect to the projection and recesses described, is their distribution and arrangement in the contour of the frame, so that the two frame members being identical in every 70 respect when applied face to face on the curtain and glass engaged between them, will present a recess upon one frame member opposite and adapted for engagement of a corresponding projection on the other 75 frame member. This is accomplished by distributing the recesses and projections of both sorts in the contour of the frame member symmetrically with respect to the middle longitudinal line, and also with respect to 80 the middle transverse line about which the frame members, with respect to their contour, are symmetrical. This results in the alternation of projections, 9, and recesses, 10, on both sides and ends of the frame 85 member, as may be seen in Figure 1. The location of the ribs as described,—that is, in the same relation to two diagonally opposite corners of the frame gives the same result with respect to this feature, namely, 90 that the two frame members are identical in form so that they may be cast or stamped in the same mold or die, and that the two frame members may be applied to each other, at either of two relative positions 180 95 degrees apart about the section of the two axes about which they are symmetrically formed.

Figure 5 shows a modification consisting in substituting cylindrical, and preferably 100 tubular, gaskets, 5^x, for the angular gasket shown in the other figures, and correspondingly changing the form of the grooves in which they are seated from right angular to half circular in cross section.

105 The specific purpose of the manner and means shown for holding the glass in the frame is that the edge of the glass shall not abut against any stopping means, but, on the contrary, the jarring of the glass in its own plane which tends to cause endwise movement, which is the sort of jarring to which a vehicle window is most exposed, and which is the cause of most breakage of carriage curtain windows, is cushioned, not by 110 the edge being stopped on a compressed cushion, but by the flexible yielding of the rubber gasket which grips the surface of the glass so firmly that the latter does not slip on the gasket, but the latter is stretched 115 and bends in the plane of the edgewise movement which the glass receives from the jarring; and in such movement the glass cannot strike its edge against the frame at any point. In effect, the glass is held suspended 120 by elastically yielding suspending means 125 consisting of a compressed gasket pressing its vertical surfaces.

I claim:—

1. A carriage curtain window frame com- 130

prising two frame members encompassing the window opening, adapted for clamping a window glass between them, each member having at the edge toward the window opening a rabbet whose depth in the direction of the plane of the glass is such as to provide a substantial depth of unoccupied or clearance space all around the edge of the glass between the same and the peripheral shoulder of the rabbet; yielding gaskets seated upon the other shoulder of the rabbet bearing on the margin of the glass at the opposite sides thereof; and means for securing the two frame members together with the glass and 15 gaskets gripped between them; whereby the glass is gripped solely by the gaskets and held suspended by the frictional grip of the latter without edgewise support or lodgment.

20 2. In the construction defined in claim 1, foregoing, the frame members having grooves in the face or shoulder of the rabbet facing the plane of the glass and encompassing the window opening, the gaskets being 25 engaged in said grooves for positioning them

against lateral movement in the direction of the plane of the glass.

3. In the construction defined in claim 1, foregoing, the frame members having grooves in the face or shoulder of the rabbet 30 facing the plane of the glass and encompassing the window opening, the gaskets being engaged in said grooves for positioning them against lateral movement in the direction of the plane of the glass, the grooves 35 being angular in cross-section, and the gaskets having the side opposite that which is near the groove flat-faced substantially in the plane of the glass, said face being in a plane substantially at right angles to a plane 40 bisecting the groove, for affording extended area for frictional grasp of the gaskets on the glass and for equalizing the yielding of the gaskets in the plane of the glass under 45 compression.

In testimony whereof, I have hereunto set my hand at Chicago, Illinois, this 22nd day of September, 1921.

LAWRENCE C. NELSON.
